UNITED STATES PATENT OFFICE.

LANE GIST, OF LAKE CITY, IOWA.

WATERING-TROUGH.

SPECIFICATION forming part of Letters Patent No. 680,772, dated August 20, 1901.

Application filed December 31, 1900. Serial No. 41,726. (No model.)

To all whom it may concern:

Be it known that I, LANE GIST, a citizen of the United States, residing at Lake City, in the county of Calhoun and State of Iowa, have 5 invented a new and useful Improvement in Automatic Watering-Troughs, of which the following is a specification.

This invention is an improved construction of watering-trough, the object being to provide a simple and efficient means for maintaining the water-supply in a stock-trough at a definite level; and with this object in view the invention consists in the peculiar construction of the various parts and in their 15 novel combination and arrangement, all of which will be fully described hereinafter and pointed out in the claims.

In the drawings forming part of this specification, Figure 1 is a view showing the practical application of my invention. Fig. 2 is a vertical sectional view of the apparatus, and Fig. 3 is a sectional view showing a slightly-modified form of construction.

In carrying out my invention I employ a 25 receiving-tank A, which may be of any desirable size and shape and into which the water is led from any suitable source through an opening A'. The discharge-tank B is arranged adjacent to the tank A and has an annular trough C supported thereon, the central raised portion C' having a series of openings C², through which the water passes into the annular trough, and it is from this annular trough that the stock drink. A pipe D leads from the tank A and connects with the larger pipe D', having a valve-seat E in the upper end thereof adapted for engagement with the ball-valve F, which is connected to a float G, operating in a discharge-tank B 35 and working up and down in the raised portion C' of the trough C. It will be understood from the foregoing description that the water will flow from the storage or receiving tank A into the discharge-tank B and out 40 through the opening C² into the annular trough, and when the water reaches a predetermined level the float G will cause the valve F to seat upon the valve-seat E and cut off the supply of water; but as soon as the sup-

ply falls below the predetermined level the 50 valve will become unseated, permitting more water to flow through and reestablish the predetermined level.

By constructing the discharge-tank and trough in the manner described I am enabled 55 to arrange the float-valve within the same in a very compact manner. In Fig. 3 I have shown a slight modification, in which A² is the receiving-tank and B² the discharge-tank arranged therein, said discharge-tank having 60 a tubular opening B³, in which is located the valve-seat E', in which works the valve F', connected to the float G', arranged within the discharge-tank, said discharge-tank having a pipe B⁴ leading therefrom into the trough C³. 65 The operation of the modified form is exactly the same as the operation of the device shown and described in Figs. 1 and 2.

Having thus fully described my invention, what I claim as new, and desire to secure by 70 Letters Patent of the United States, is—

1. An automatic watering device, comprising a receiving-tank, and a discharge-tank, and the pipes connecting the said tanks, the annular trough arranged upon the top of the 75 discharge-tank and having a central raised portion provided with openings, a float arranged in the discharge-tank and adapted to move up and down with the central raised portion of the annular trough, and the valve 80 connected to said float, substantially as shown and described.

2. In an automatic watering device, the combination with the receiving and discharge tanks, and pipes connecting the same, of the 85 annular water-trough arranged upon the discharge-tank, and having a central raised portion provided with openings, the float arranged within the discharge-tank and adapted to operate in the central raised portion, 90 the valve-seat located in the upper end of the pipe leading into the discharge-tank, and the valve adapted to coact with the said seat, substantially as shown and described.

LANE GIST.
